AUXILIARY TRAY FOR REFRIGERATOR SHELVES

Albert F. Romano, 1706 W. Steigere St., Norristown, Pa.

Filed Apr. 9, 1957, Ser. No. 651,726

2 Claims. (Cl. 211—139)

The present invention relates to a shelf or tray such as is ordinarily included in a refrigerator, and is concerned primarily with an auxiliary tray that is intended to be mounted on and supported from a main shelf that is movably mounted in the refrigerator.

At the present time, there are two main types of movable trays that are included in a refrigerator. In one form, the tray is semicircular in shape and is mounted within the refrigerator cabinet for pivotal movement. Thus, when the refrigerator is closed, the semicircular edge of the main tray is disposed within the cabinet. After the refrigerator is opened, the tray is rotated on its axis to move the semicircular tray outwardly into accessible position.

In other types of refrigerators including rectangularly shaped shelves, it is the practice to mount one or more of the shelves for rolling or sliding movement so that it may be moved outwardly to afford better access thereto.

The modern housewife often has need of storing various types of small articles within the refrigerator. Among such might be noted dessert dishes, fruit cups, custard jars and the like. Each of such articles in itself occupies but a small amount of space. Yet, there is often need for storing a large number of such articles within the refrigerator. The present invention is founded on the belief that if one of the main movable shelves of a refrigerator is provided with an auxiliary tray along an edge thereof its utility is enhanced and it is possible and entirely practical to store a large number of the small receptacles above noted within the refrigerator with a maximum of convenience.

With the foregoing conditions in mind, the present invention has in view as its foremost objective the provision of a movable refrigerator shelf that is provided with an auxiliary tray along an edge thereof and in spaced relation above the main tray. With this arrangement, small receptacles may be stored on the main tray beneath the auxiliary tray and also on top of the auxiliary tray. Moreover, being located on the periphery of the shelf, the latter may be moved to bring the auxiliary tray into a position in which it is conveniently accessible.

More in detail, the invention has as an object the provision of a rotating refrigerator tray having a semicircular peripheral edge that is provided with an auxiliary tray that conforms in shape to said semicircular edge and which is supported from the main tray above the portion immediately adjacent to the semicircular edge.

Still another object of the invention is to provide a sliding or rolling refrigerator tray of rectangular shape having side edges with an auxiliary tray along one or both of said side edges.

There may be occasions when the auxiliary tray is not needed and it is desired to remove it from the main shelf. Accordingly, another object of the invention is to provide an auxiliary tray for a removable refrigerator shelf

2

of the character above noted, which is held in effective position by removable supporting elements.

Various other more detailed objects and advantages of the invention such as arise in connection with carrying out the above-noted ideas in a practical embodiment, will in part become apparent and in part be hereinafter stated as the description of the invention proceeds.

The invention therefore comprises a combination of a movable refrigerator tray together with an auxiliary tray that is supported from said main tray over an edge portion thereof by removable supporting means.

For a full and more complete understanding of the invention, reference may be had to the following description and accompanying drawing wherein:

Figure 1 is a perspective view of a rotating refrigerator shelf with an auxiliary tray applied thereto in accordance with the precepts of this invention;

Figure 2 is another perspective illustrating the main shelf, the auxiliary tray and supporting elements in exploded relation;

Figure 3 is a top plan view of the auxiliary tray per se;

Figure 4 is a detailed section through one side of the auxiliary tray and main shelf and is taken about on the plane represented by the line 4—4 of Figure 1;

Figure 5 is a perspective view of a sliding or rolling shelf with auxiliary trays applied to the side edges thereof;

Figure 6 is another perspective showing the main shelf, auxiliary trays and supporting means in exploded relation; and

Figure 7 is a detailed vertical section through one of the auxiliary trays and a portion of the main shelf.

Referring now to the drawings and first more particularly to Figures 1 to 4 inclusive, a revolving-type refrigerator shelf is therein illustrated and referred to by the reference character 10. The shelf 10 is mounted on a vertical post 11 in a well-known manner for rotative movement. This shelf 10 has a straight edge 12 and a curved edge 13 that is somewhat in excess of a semi-circle.

Referring now more particularly to Figure 4, the curved edge 13 is shown as being defined by a raised bead 14 and a depending skirt or flange 15.

An auxiliary tray is shown at 16. It has a shape corresponding to the curved edge 13, being slightly greater than a semicircle and is defined by an outer curved edge 17, an inner curved edge 18 and an end edge 19.

In order to support the auxiliary tray 16 from the main shelf 10, a plurality of supporting members are employed. Each of these supporting elements is referred to in its entirety by the reference character S. As shown in Figure 1, three of the supporting members S are employed, although this number may be varied without departing from the spirit of the invention.

As shown in Figure 4, the edges 17 and 18 of the tray 16 may take the form of downturned flanges 20 which provide an annular track or recess for receiving a pedestal 21. The pedestal 21 is secured to the top of a vertical upright 22 that constitutes a part of the support S. Secured to the lower end of the upright 22 is a curved bracket member 23 that fits over the bead 14, terminating in a lip 24 which engages the upper surface of the tray 10. The lower end of the upright 22 is formed as a bend 25 to which is integrally joined an upturned flange 26. The recess provided by the flange 26 and bend 25 receives the skirt 14 of the main shelf 10.

The operation and mode of using the auxiliary tray above described is believed to be obvious from the illustration of the drawings and description of parts given. However, they may be briefly outlined as follows:

When the use of the auxiliary tray 16 is required, the necessary number of the supports S are applied in effective

position over the bead 14. The auxiliary tray 16 is then positioned with the pedestals 21 being received in the recess defined by the flanges 20. When so positioned, the space beneath the auxiliary tray 16 is available for receiving small receptacles and additional such receptacles may be placed on the tray 16 itself. Obviously, the auxiliary tray 16 is brought into accessible position by rotating the main tray 10.

Referring now more particularly to Figures 5, 6 and 7, the form of the invention as applied to a sliding or rolling tray will be described.

A main shelf 27 of rectangular formation has side edges defined by flanges 28 and 29. It is intended that this shelf 27 be mounted in a refrigerator cabinet for rolling or sliding action so that it may be moved outwardly or inwardly as occasion demands.

While the main shelf 27 may take any of many structural forms, one type of shelf which is meeting with widespread approval is made up of a plurality of cross bars 30 that are anchored to a front edge bar 31 and a rear edge bar 32 in a well-known manner. Such an open framework permits of circulation of air within the refrigerator.

A pair of auxiliary trays are each referred to in its entirety by the reference character T. Each of the trays T includes side edge bars 33 and 34, end bars 35 and 36 and inner cross bars 37.

The auxiliary tray T on one side is supported from the flange 28 by a pair of supporting members, each comprising a vertical upright 38 terminating in a U-shaped flange 39 at the top and a clip 40 at the bottom. The clip 40 is intended to encompass the flange 28 while the U-shaped member 39 receives the edge bar 33.

The edge 34 may be supported by an inner support 41 that is formed at the top with a curled-over bead-like part 42 that is fitted about the side member 34 and has at the bottom a U-shaped clip 43 that is slipped onto one of the cross bars 30.

It is evident that the trays T are removable due to the fact that the supporting members 38 are removable. Moreover, even with the members 38 in position on the flanges 28 and 29, trays T may be swung downwardly much in the manner of a drop leaf table, simply by removing the U-shaped clips 43 from the bars 30 which

they engage and swinging them upwardly, after which the trays T may be swung downwardly to assume an out-of-the-way position at the side.

While preferred specific embodiments of the invention are hereinbefore set forth, it is to be clearly understood that the invention is not to be limited to the exact constructions, mechanisms and devices illustrated and described because various modifications of these details may be provided in putting the invention into practice within the purview of the appended claims.

What is claimed is:

1. A refrigerator construction comprising a generally planar horizontally disposed main shelf having a generally semicircular edge and a straight edge extending between the ends of said semicircular edge, means mounting said main shelf for rotation about a generally vertical axis generally through the center of curvature of said semicircular edge, an upstanding relatively wide bead extending along said semicircular edge and having a transversely arcuate upper surface, a relatively narrow skirt extending along and depending from the outer region of said bead, a plurality of spaced resilient clips each extending vertically on the exterior of said skirt having its lower end portion bent upward about a relatively short radius for snug engagement about the lower edge of said skirt and having its upper end portion bent downward about a relatively large radius snugly engaged over said bead, a standard upstanding from each of said clips, and an auxiliary shelf of semiannular configuration seated on the upper ends of said standards.

2. A refrigerator construction according to claim 1, in combination with a pair of depending flanges extending respectively along the longitudinal edges of said auxiliary shelf for retaining the latter in position on said standards.
